(57) **CLAIM**

The ornamental design for an instrument for medical or laboratory diagnosis as shown and described.

DESCRIPTION

The patent or application file contains at least one drawing executed in color. Copies of this patent or patent application publication with color drawings will be provided by the office upon request and payment of the necessary fee.

FIG. 1 is a front perspective view of an instrument for medical or laboratory diagnosis showing a first embodiment of our new design.

FIG. 2 is a front view thereof.

FIG. 3 is a rear view thereof.

FIG. 4 is a side view thereof.

FIG. 5 is a side view of the side opposite that shown in FIG. 4.

FIG. 6 is a top view thereof.

FIG. 7 is a front perspective view of an instrument for medical or laboratory diagnosis showing a second embodiment of our new design.

FIG. 8 is a front view thereof.

FIG. 9 is a rear view thereof.

FIG. 10 is a side view thereof.

FIG. 11 is a side view of the side opposite that shown in FIG. 12; and,

FIG. 12 is a top view thereof.
